FREDERICK J. PEASE AND HARLOW H. PEASE, OF WAUWATOSA, WISCONSIN, ASSIGNEES
TO CLUM MANUFACTURING COMPANY, OF MILWAUKEE, WISCONSIN, A CORPORA-
TION OF WISCONSIN

SASH PULLEY

Application filed October 30, 1930. Serial No. 492,109.

This invention relates to improvements in sash pulleys.

It is the object of the invention to provide a novel sash pulley casing which may be driven to a fit within a single opening in a window frame, and which includes integral means for anchoring itself within said opening independently of the use of screws or other fastening devices, thus cheapening the cost of manufacture of the pulley and greatly reducing the expense of positioning it within a window frame.

In the drawing:

Figure 1 is a view of the pulley in place within a frame which appears in vertical cross section, a portion of the pulley casing being broken away to expose a sheave therewithin.

Figure 2 is a front elevation of the pulley assembly as it appears within the frame.

Figure 3 is a view taken in section in the plane indicated at 3—3 in Fig. 1.

Like parts are identified by the same reference characters throughout the several views.

The pulley casing 5 is in the form of a flattened tube having rounded sides and ends and comprising a pair of stamped shells 6 and 7 having complementary margins 8 continuous about the top and ends of the pulley casing and across the intermediate portion of the bottom thereof, but cut away at 9 to provide openings through which the sash rope 10 may pass.

The shells 6 and 7 are joined by longitudinally spaced rivets 11, of which the heads are disposed in recesses 12 in the faces of the respective shells, so that they will not interfere with the movement of the shell into the opening provided therefor at 13 in the frame member 14. Within the pulley casing the rivets 11 provide shaft portions upon which the sheaves 15 are rotatable to carry the rope 10.

At the front of the pulley casing the opening at 9 is bounded by a shoulder 16, as shown in Figs. 1 and 2. In order that the device may present a finished appearance without the use of a mounting plate or bezel, it is desired that the shoulder 16 be flush with the

front of frame member 14. To this end means is provided for limiting the movement of the pulley casing through the frame member 14, and this means preferably constitutes complementary ribs 18 formed integrally in the walls of the respective shells which comprise the pulley casing. It will be obvious that when the pulley casing is driven through a hole in the frame member 14 closely conforming in size to the casing, the engagement of the rib 18 with the frame member will act as a positive stop to prevent inward movement of the casing beyond the desired position.

In order to prevent the casing from outward displacement we provide at 20 prongs or points pressed outwardly from the faces of each of the shells 6 and 7. The shape of these prongs is broadly immaterial, but it is desirable that each should include a point projecting toward the front of the casing, as at 21. The natural resilience of the metal used in forming the casing will tend to force the pointed portions of the prongs outwardly into the wood of the frame member 14 and, although the prongs will not enter the wood material during the inward movement of the pulley casing, they will catch and resist any tendency of the casing to move outwardly, so that after the casing is once in place it can only be removed by the application of very substantial pressure.

It is not necessary that the frame member 14 be made of wood, since a metal frame member having an opening suitable for a pulley casing embodying this invention may also be made to be engaged by similar prongs.

When a pulley casing embodying this invention is fully seated within an apertured frame member, the engagement of its bead 18 with the frame member will tend to hold the casing against oscillation in one direction, and the integral prongs will be rendered effective in the mere act of driving the pulley casing into the frame to secure the casing against accidental withdrawal and to maintain the desired seat of its rib 18 with the face of the frame.

We claim:

In a pulley adapted for insertion in a frame

aperture, a pulley casing composed of complementary shells formed of sheet metal and each comprising a side, top, bottom and ends, the bottom being cut away at each end to provide sash rope openings, and each shell having intermediate its ends and adjacent one of the openings a rib portion formed by pressing the walls of the casing outwardly.
